UNITED STATES PATENT OFFICE.

JOSEPH ARDO, OF NEWHALL, WEST VIRGINIA, ASSIGNOR OF ONE-HALF TO KALMAN HORVATH, OF NEWHALL, WEST VIRGINIA.

SUBMERSIBLE FLYING BOAT.

1,421,369.

Specification of Letters Patent. Patented July 4, 1922.

Application filed October 28, 1921. Serial No. 511,144.

To all whom it may concern:

Be it known that I, JOSEPH ARDO, citizen of the United States, residing at Newhall, in the county of McDowell and State of 5 West Virginia, have invented certain new and useful Improvements in Submersible Flying Boats, of which the following is a specification.

This invention relates to a submersible 10 flying boat, and it has for a general object to provide a boat capable of traveling in the air, or on or under the water.

A further object is to arrange the lifting planes, which sustain the boat in the air, in 15 a manner to permit of the same being folded backward when the boat is to be submerged.

A further object relates to the provision 20 of novel means for raising or lowering the boat in the water.

For further comprehension of the invention, and of the objects and advantages thereof, reference will be had to the following description and accompanying drawings, 25 and to the appended claims in which the various novel features of the invention are more particularly set forth.

Fig. 1 of the drawings is a side view, with 30 parts broken away to show interior mechanism, of a submersible flying boat constructed according to my invention.

Fig. 2 is a front view thereof.

Fig. 3 is a partial plan view, with the lifting plane sections, or wings, folded back.

Referring now to the drawings, 10 indicates the hull of my improved submersible flying boat, this hull being constructed of usual material and being of usual streamline form. The hull is provided with a conning tower 11, having front and rear porting holes 12, and a door 13. A periscope 14 of ordinary construction is mounted on the conning tower 11. In the top of the hull 10 are 15 mounted a pair of vertical stub-shafts 18 to which are fixed rigid arms such as 19 to which the plane structure of the boat is rigidly attached. As here shown the boat is shown as provided with upper and lower 20 planes 20 and 21 divided into two wings or sections. The lower wings are fixed on the arms 19 adjacent their inner rear corners, while the upper wings are rigidly braced to the lower ones by the struts 22 and tie 25 rods 23.

Secured to the undersides of the wings 21 are downwardly projecting studs 25 which are adapted to be engaged by hooks or claws 26 carried on the upper ends of compound rock-shafts 27 to hold the wings 60 in transversely extended position. The wings are also provided near their rear edges with a second pair of studs 28 adapted to be engaged by hooks or claws 29 fixed on the upper ends of compound rock-shafts 27 65 supported by a bracket 31 on the hull to hold the wings in the backwardly folded position shown in Fig. 3. The rock-shafts are here shown as comprising an outer tube 30 and an inner tube 30' on which the hooks are 70 mounted, these hooks are closed together by springs 33. The shaft elements 30, 30' are adapted to be rocked, to swing the hooks out of engagement with the studs 28, by arms 75 34 fixed to the underside thereof and connected by cords 34' to a common operating lever 34^a provided with ordinary locking means such as 34^b. The hooks 25 are also released and held by similar means. 80

For travel through the air the boat is provided with a pair of air propellers 35 fixed to the rear ends of shafts 36 suitably journaled in a framework 37 rigid with the wing structure between the upper and lower wings. 85 Journaled in the framework 37 of each wing, below and parallel to the shaft 36, is a second shaft 38 which has a drive connection with said shaft 36 by means of a sprocket chain 39 looped over suitable 90 sprocket wheels on the respective shafts. Upon the forward ends of shafts 38 are fixed bevel gears 40 which mesh with like gears 41 on the outer ends of transverse shafts 42 whose inner ends have toothed clutch elements 43 fixed thereto and adapted to engage with or disengage from, like clutch elements 44 on the ends of a shaft 45 driven by a suitable engine (not shown) contained within the boat. 95

For swinging the wings between their two positions I provide on the lower end of each shaft 18 a bevel gear 50 engaged by a bevel pinion 51 journaled in a suitable bearing bracket 52 and having fixed co-axially thereto a crank handle 53 whereby it may be rotated.

For vertical steering of the aeroplane in the air I mount on the rear end of the hull 10 an elevator 54 of ordinary construction 110

and operated by the usual controls, while lateral steering both in the air and water is effected by means of a rudder 55 at the rear of hull 10 and operated in the usual manner. For propelling the boat through the water a suitable propeller 56 is mounted at the rear of the hull and driven by the boat engine through suitable connections.

For submerging or raising the boat I provide within the hull 10 a plurality of longitudinally extending cylinders 60 whose forward ends open through the hull wall, and may have screens 16 placed thereover. Each of these cylinders has a piston such as 62 therein and having a rearwardly extending piston rod 63 whose rear end passes through a fixed support 64. The piston rod 63 has a series of longitudinally spaced notches 65 formed therein and engaged by a pawl 66 pivoted on the support 64 to hold the piston against backward movement. As will be understood, the piston may be set at different distances from the mouths of the cylinders 60 and the quantity of water 25 contained therein thereby varied. For forcing the pistons forward I provide a series of tanks 68 adapted to contain compressed air supplied thereto, when the boat is on or above the surface of the water, by an air 30 compressor 69. These tanks have pipes such as 70 leading to the respective cylinders, each pipe having a control valve such as 71 mounted thereon. To assist in raising and lowering the boat in the water I also 35 provide a horizontally arranged propeller 73, located above the front end of the hull 10, and driven by suitable connections from the boat engine. When the boat is designed for use in warfare it may be equipped with 40 a pair of machine guns carried in the conning tower 11 and facing rearwardly and forwardly respectively, the ends of the conning tower being provided with doors 75 which may be swung open to allow the gun 45 to be used, the rear gun being indicated at 76 in Fig. 1.

Having thus described my invention what I claim as new and desire to protect by Letters Patent of the United States is as 50 follows:

1. In a submersible vessel, a hull, a series of cylinders opening at one end through

said hull, pistons in said cylinders, means for locking said pistons in different adjusted positions against inward movement in said cylinders said means permitting free outward movement of the pistons in the cylinders, and other means for moving said pistons outward in said cylinders.

2. In a submarine, a series of longitudinally extending cylinders having their forward ends opening through the hull of the submarine, pistons in said cylinders, and means for setting said pistons in different positions longitudinally of the cylinders, said means including notched piston rods connected to said pistons and pawls adapted to engage in the notches in the piston rods to prevent rearward movement but permit free forward movement of said piston rods, and means for supplying compressed air to said cylinders behind said cylinders.

3. In a flying machine, a body, a pair of wings on said body and adapted to be extended transversely of said body or to fold backward thereover when not in use, propellers mounted on said wings, a motor in said body, and releasable drive connections between said motor and propellers.

4. In a flying machine, a body, a pair of wings on said body and adapted to be extended transversely of said body or to fold backward thereon when not in use, propellers mounted on said wings, a motor in said body, and releasable drive connections between said motor and propellers, said connections including clutch elements adapted to automatically engage and disengage as the wings are changed from one position to 90 the other.

5. A submersible flying boat comprising a closed hull, and a pair of wings on said hull and adapted to be extended transversely or to fold backward thereover when 95 not in use, propellers mounted on said wings, shafts for rotating said propellers, a drive shaft mounted on the boat hull, and releasable clutch connections between said drive shaft and first mentioned shafts.

In testimony whereof I have affixed my signature.

JOSEPH ARDO.
